UNITED STATES PATENT OFFICE.

JAMES B. KERR, OF FLINT, MICHIGAN.

WINDOW-SIGN.

SPECIFICATION forming part of Letters Patent No. 341,249, dated May 4, 1886.

Application filed September 16, 1885. Serial No. 177,266. (No model.)

To all whom it may concern:

Be it known that I, JAMES B. KERR, of Flint, in the county of Genesee and State of Michigan, have invented new and useful Improvements in Window-Signs; and I do hereby declare that the following is a full, clear, and exact description thereof, reference being had to the accompanying drawing, which forms a part of this specification.

10 This invention relates to certain new and novel improvements in window-signs; and the invention consists in the peculiar construction and arrangement of the parts, whereby the sign is removably secured in the window and adapted to be swung open or away from the window, all as more fully hereinafter set forth.

Window-signs, as usually applied, are either painted upon the glass or so-called "enamel letters" are cemented thereto. In 20 these cases frost, sweat of window, and washing causes the letters to break or wear off, as they cannot be removed.

It is the object of my invention to provide a means for securing a sign in a window, where- 25 by such sign can be removed when it is desired to clean the window.

In the accompanying drawing, which forms a part of this specification, my improved device is shown in elevation.

30 A represents a suitable frame, made in any desired design, to which the letters of the sign

are soldered or otherwise rigidly secured. At each end of the frame A, and rigidly secured to it, are the plates a, which are made in the form of the female portion of a hinge, which 35 are designed to engage with the male portions b of a hinge secured to the window sash or frame, the parts being secured together by removable pintles c.

It will readily be seen that by removing one 40 of the pintles the sign can easily be swung back away from the glass, so that it can be cleaned, and, the sign not coming in contact with the glass, the letters can easily be kept bright and clean, and the sign can readily be 45 moved upon changing place of business.

I am aware that street-lamps have been provided with hinged frames carrying the letters denoting the street, and make no claim to such, broadly. 50

What I claim as my invention is—

The combination, with the frame A, upon which the letters are rigidly secured, and the plates a, secured to the ends of said frame, of the male portion b of the hinges and the removable pintles c, all substantially as herein shown and described, and for the purpose specified. 55

JAMES B. KERR.
